US00D766108S

(12) **United States Design Patent** (10) **Patent No.:** **US D766,108 S**
(45) **Date of Patent:** **** Sep. 13, 2016**

(54) **PACKAGING**

- (71) Applicant: **KRAFT FOODS R & D, INC.**,
Deerfield, IL (US)
- (72) Inventors: **Rosie Brown**, Birmingham (GB);
Julian Sellers, Birmingham (GB); **Glen Dutton**, Huddersfield (GB)
- (73) Assignee: **MODELEZ UK R & D LIMITED**,
Birmingham (GB)
- (**) Term: **14 Years**
- (21) Appl. No.: **29/507,528**
- (22) Filed: **Oct. 28, 2014**

(30) **Foreign Application Priority Data**

(57) **CLAIM**

The ornamental design for packaging, as shown and described.

DESCRIPTION

FIG. 1 is a perspective view of packaging, showing our new design;

FIG. 2 is a front elevation view thereof;

FIG. 3 is a rear elevation view thereof;

FIG. 4 is a side elevation view thereof, the opposite side view being a mirror image thereof;

FIG. 5 is a top plan view thereof;

FIG. 6 is a bottom plan view thereof;

FIG. 7 is a perspective view thereof, as shown in an alternate configuration; and,

FIG. 8 is a second perspective view thereof.

The broken lines shown represent unclaimed subject matter and form no part of the claimed design.

1 Claim, 7 Drawing Sheets
